United States Patent Office

Des. 183,148
Patented July 1, 1958

183,148

COMBINED TOY AIRPLANE AND BOMBSIGHT

David L. Severson, Madison, Wis.

Application April 5, 1957, Serial No. 45,598

Term of patent 7 years

(Cl. D34—15)

FIG. 1

FIG. 2

FIG. 3

Fig. 1 is a top plan view of a combined toy airplane and bombsight, showing my new design.

Fig. 2 is a side elevational view thereof, the opposite side having substantially the same appearance.

Fig. 3 is a front elevational view thereof.

I claim:

The ornamental design for a combined toy airplane and bombsight, as shown and described.
